UNITED STATES PATENT OFFICE.

ARTHUR R. BOAL AND CHARLES O'BRIEN, OF NEW YORK, N. Y.

DISPLAY CASE.

Application filed October 1, 1921. Serial No. 504,645.

To all whom it may concern:

Be it known that we, ARTHUR R. BOAL and CHARLES O'BRIEN, citizens of the United States, and residents of New York city, in the county of New York and State of New York, have invented certain new and useful Improvements in Display Cases, of which the following is a specification.

Our invention relates to display stands 10 or cases, and is particularly directed to a device of this type in which small packages or articles may be directly displayed on the counter or show-case to attract the eye of prospective customers.

15 Stands and cases of this type are largely employed for the display of small package goods such as are sold in drug, grocery, confectionery and similar stores; and those in common use are generally open so that the 20 goods may readily be removed. This arrangement, while convenient and effective, permits frequent pilfering of the small articles from the open holders, a practice which in some cases has become sufficiently 25 extensive to be serious.

One object of our invention is to provide a display case or stand for small articles or packages so arranged that unauthorized removal of the goods therefrom is very difficult. An ancillary object is to provide such 30 a holder from which the merchant can readily and rapidly remove the articles as wanted.

Another object is to evolve a case which 35 may be readily and rapidly refilled; and in the preferred form we have provided such a case adapted for the display of articles in their original container, so arranged that a new container can be easily and speedily 40 inserted when the old one is empty.

In the preferred form disclosed, we have furthermore provided a case in which the unsightly appearance often caused by the removal of most of the packages from 45 a display holder is largely eliminated, our case retaining its attractive display appearance until the packages are all removed.

We have furthermore accomplished these 50 and other objects which will be apparent while retaining to a high degree the valuable features of cases or stands of this type; more particularly, our stand is attractive in appearance, presents the goods in an attractive manner, is durable and may 55 be manufactured as cheaply, strongly or

with as much surface finish and decoration as the individual user may desire.

Other objects and advantages of our invention will be apparent from the following description, taken in connection with the 60 accompanying drawings, in which:

Fig. 1 is a perspective view of a preferred form adapted for the display of elongated rectangular packages, in display position,

Fig. 2 is a vertical section from front to 65 back through a similar device, the position for removal and refilling being shown in dotted lines, and

Fig. 3 is a detail of a hinge construction.

Our improved case consists generally of 70 an article support adapted to retain the articles in inclined position for display, and to swing downwardly and rearwardly for ready removal of the articles. This is supported on a suitable body or framework, 75 and preferably has retaining means across the front of the articles or packages to prevent removal thereof. In the preferred form the body of the case includes a base 10, sides 11, a low front 12, and a top 13, constructed of any desired material, such as metal, wood, or composition, the preferred form shown being of paper composition with the exposed faces covered with metal, and the edges reinforced with metal strips, 80 except that the front wall 12 is entirely of metal.

The articles are carried on a swinging support 14 movably connected to the body so as to swing from inclined display position to horizontal removal position. One 85 convenient and economical method of providing a connection between the support and the body includes ears 15 along the lower edge of support 14, and a pintle wire 16 90 passing through the ears and fastened at its ends to the body adjacent sides 11, as by turning the ends at right angles to lie along said body and clamping them in upturned tongues 17 formed from the metal edging 100 18 of the body sides. Obviously this arrangement can be materially varied.

We also provide means of the latch type 105 for retaining the support 14 in elevated position. This may include a swinging latch 19 pivotally mounted in an ear 20 on the body top 13, the latch being provided with a downturned retaining extension 21, and if desired with a check extension 22 to limit the upward movement of the latch. The 110

specific construction shown, in which the latch is made of round wire working loosely in ear 20, does not require the use of a spring; but obviously a great variety of other latches may be substituted therefor without affecting the operation of the rest of the device.

Various means for holding the articles, which in the drawings consist of the rectangular elongated packages 23, may be provided on support 14. As the packages illustrated are contained in the lower part of an ordinary cardboard box, we employ for the purpose rail 24 mounted on the support 14, the rail being so arranged and located that when the support is in display position the lowermost package 23 will be in position just above the front 12 of the body.

We prefer to provide across the front of the body means for retaining the packages therein to prevent unauthorized removal. This is conveniently accomplished by employing a glass front for the case, which may be mounted in any desired manner. In the form shown the glass 25 is mounted by adhesive on the front or upper edges of the body top, sides and front, a cushioning strip 26, preferably of felt, being interposed to protect the glass to some extent against breakage. While this method of mounting the glass is highly attractive, obviously other arrangements may be substituted.

In the preferred form we also provide means for masking the upper part of the container or space provided for the articles 23, so that partial depletion will not seriously affect the attractive appearance of the case. For this purpose we provide a cover for the upper portion of the case opening which preferably includes a label or advertisement 27; and a transverse sheet metal support 28 for the label may also be included, extending across the container at a suitable distance from the glass, and mounted at its opposite ends on the sides 11 of the body.

Any suitable means for supporting or mounting the body may be used, the form shown having supporting bosses 29 mounted on the base, as by nail projections 30 extending from the bosses into the base 10.

In use the support 14 is maintained in latched position as shown in Figs. 1 and 2; and it will be apparent that the articles 23 can only be stolen by unlatching and lowering the support and reaching around to the back of the case, the difficulty of this operation providing a substantial deterrent to would-be pilferers. On the other hand, the articles are very readily and rapidly re-

moved for sale, as latch 19 can be lifted and the support 14 lowered by a single easy movement of one hand; and all of the articles will be readily accessible when the support is lowered, the arrangement of the support and rail 24 providing adequate hand space to reach articles at the very front of the case. As articles are removed those remaining will necessarily gravitate to the bottom of the support, the empty space being shielded by label 28 until a substantial part of the articles are sold; and even when empty space appears below the label, the attractive appearance of the label combined with the appearance of the articles remaining in the case will still render the device generally attractive.

When all the articles are sold the case is refilled with the greatest ease by sliding the empty container out and replacing it with a filled container in the manner indicated in dotted lines in Fig. 2.

While we have described the preferred form of our invention and indicated certain variations therein, it will be apparent that numerous other changes and rearrangements may be made within the scope of our invention. For instance, we have not described any means for permanently locking the goods in the case; and we have shown an arrangement suitable for small packages. Furthermore, we have disclosed a body which is provided with enclosed sides and front and is of substantial appearance, being adapted to be placed on a counter or a show-case; but these features may obviously be altered to suit particular requirements or tastes. Numerous other changes will be apparent to those skilled in the art, and come within the scope of our invention as set forth in the following claim.

We claim:

A display case comprising a box-like structure having an open back and a rearwardly inclined front wall of transparent material, a support adapted to hold a plurality of articles pivotally mounted within the case and adapted to be held in display position beneath the said front wall and to be swung downwardly to permit removal of the articles of merchandise therefrom, means for holding the support in display position and means for masking the upper portion of said support.

Signed at New York city, in the county of New York and State of New York, this 15th day of September, A. D. 1921.

ARTHUR R. BOAL.
CHARLES O'BRIEN.
